RAZOR BLADE RECONDITIONING DEVICE

Charles L. Wilcox, Atlanta, Ga.

Application March 21, 1935, Serial No. 12,219

2 Claims. (Cl. 51—80)

This invention relates to improvements in devices adapted for use in the reconditioning of razor blades primarily of the thin, flexible, double-edged type, wherein a blade to be reconditioned is disposed in arcuate or flexed position for pressure contact against non-resilient honing rollers partially rotatable by oscillating contact against the user's palm or fingers or suitable tractive surface.

It is an object of this invention to provide a device of the class described whereby the sharpening, reconditioning, or stropping of thin, flexible, double-edged razor blades is greatly simplified and whereby the use of aggregate parts to accomplish the desired result is substantially eliminated. Likewise, an object of the invention is to provide a device which is sturdy, but which is cheap and simple to construct.

In the drawing, Figure 1 is a plan view of a preferred embodiment of my invention.

Figure 2 is a side elevation thereof.

Figure 3 is a sectional view taken on the line 3—3 of Figure 1.

Figure 4 is a sectional view taken on the line 4—4 of Figure 1.

Figure 5 is an end elevation wherein the blade detention latch is shown.

Figure 6 is a cross sectional view taken on the line 6—6 of Figure 2.

Figure 7 is a cross sectional view taken on the line 7—7 of Figure 2.

Figure 8 is a fragmentary view taken similarly to Figure 3, showing the blade detention latch in closed position.

Figure 9 is a perspective view showing the device ready for the reconditioning of the razor blade annexed thereto.

Briefly, it is the concept of my invention to eliminate the complexity of the usual razor blade reconditioning operation by providing a device in which a blade of the type described may be disposed and held in flexed or arcuate position with the edges thereof in semi-resilient pressure contact against, and in accurate longitudinal alignment with, non-resilient honing rollers having circumferential portions thereof exposed for tractive engagement against the user's palm or fingers, the rollers additionally being limited in the extent of rotation effectible upon oscillation of the device.

One embodiment responsive to my invention may be more fully understood by reference to the accompanying drawing, in which, numeral 1 indicates a rigid frame comprising side members 2—2 and end members 3—3. The side members

2—2 are perforated, as at 4, to reduce the weight of the device, and the lower edges of the side members are recessed, as at 5, the reason for which being later discussed.

Mounted within the frame 1 in parallel relation to each other are a pair of shafts 6—6 suitably spaced. The shafts 6 each pass through and rest within suitable bores in one frame end 3 and are held rigid with the frame by threaded engagement of countercircumferential portions 7—7 of 10 each shaft 6—6 with threaded bores in the opposite end member 3.

Rotatively journaled on said shafts 6—6 are provided, one for each shaft, sleeves 8—8. Each sleeve carries a collar portion 9 quadrantly bored 15 and threaded, as at 10, two adjacent threaded bores 10 on each collar carrying stop screws or pins 11—11. A slotted housing 12 suitably bored for rotative reception of each collar portion 9, respectively of each sleeve 8, is mounted over 20 said collars. The collars 9—9 are free to rotate partially within the housing slot but are limited by abutment of the pins 11 against the bottom of said slot.

Rigidly annexed to each sleeve portion 8 intermediate the housing and the opposite end 3 is mounted an abrading roll 13. The length of the frame 1 and the width of the housing 12 are designed for the reception therebetween of abrading rolls sufficient in length for the longitudinal reception of ordinary razor blades. The diameter of these honing rolls is preferably such that the lower roll circumferences are exposed for traction through the recesses 5 cut in the side members 2—2, the ends of the roll being 35 protected against damage by the end members 3—3.

These rolls are composed of abrading material and present continuous, rigid, unyielding surfaces for honing of the blade. These rolls may be 40 formed from artificial stone, carborundum, or artificial slate or materials of like abrading characteristics. The surfaces preferably are smoothed to a good finish by grinding.

A support or bridge member 14 is annexed to 45 each end plate 3 and is disposed centrally between the rollers 13. This member carries a pair of studs 15 recessed at their base portions with narrow slots 16—16. The studs are longitudinally spaced on the support member for registration 50 with the apertures of the usual razor blade of the type described.

A blade placed over the studs with the apertures in registration therewith may be held in depressed position by longitudinal movement of the blade 55

in which movement the blade area adjacent the registering apertures enters the narrow slots 16 and becomes held with respect to vertical movement. The elevation of the slots with respect to 5 the elevation of the adjacent abrading rolls is preferably such that the blade when in depressed position and when being held within the slots, is in flexed or arcuate position so that the cutting edges of the blade are in resilient pressure contact with the honing surfaces of the rolls. Likewise, the longitudinal spaced position of the studs with respect to the frame should be such that the 10 blade inserted over the studs is substantially centrally located longitudinally of the honing surfaces.

To retain the blade longitudinally after the same has been disposed over the studs within the slots, a detention latch 17 is provided for engagement against one blade end. The detention latch 20 is pivotally mounted on the support member 14, being held in closed or open position by the clip spring 18 annexed to the underside of the said support member 14 by the screws 19.

For operation of the device, the blade to be reconditioned is placed over the studs 15, depressed downwardly and moved longitudinally for engagement of the blade within the slotted apertures 16. The detention latch 17 is then moved to the closed position in contact with the end of the blade. 30 With the blade held within the device in this position, the device is placed with the lower roller surfaces in contact with the fingers or palm of the user and oscillated. Blades of certain relatively stiff characteristics after mounting within 35 the device provide inherent spring resiliency against the honing surfaces for adequate honing. Blades of the type recently sold, however, are made of relatively thin and highly flexible metal and exert when mounted within the device as 40 disclosed, a pressure against the rolls which may be inadequate for successful reconditioning. In such event after mounting of the blade within the device, the thumb or index finger of the hand used to oscillate the device may be placed centrally on the blade for the exertion of additional 45 pressure so that the cutting edges are held firmly against the honing surfaces. Optionally, however, I have disclosed in my copending application, Serial Number 232,898, patented April 16, 50 1935, No. 1,998,348, the use of a pressure plate suitable for superposition over the blade whereby additional pressure may be imparted to the blade for adequate honing contact of the blade against the honing surfaces. It has been found in the 55 operation of the device that frequently five to fifteen strokes or oscillations of the device upon

the palm is sufficient to completely recondition the edge of the blade in which instance it is not necessary to turn the blade for a reconditioning of the opposite edge surfaces.

If it is desired to strop the edges of the blade held in retained position within the device, a strop of width approximately equal to that of the roller length may be pushed upwardly from the bottom of the device through the aperture between the support and the honing roll at one side of the 10 blade, and grasped by the user after projection therethrough and pulled through the device while the blade is depressed against the hone by contact of the blade with the index finger of the user. One or more operations of this nature for each 15 edge of the blade may be desirable. To smooth the upper side of the cutting edges or the sides of the cutting edges not stropped, the edges may be wiped longitudinally with the strop.

Having described my invention, I claim:

1. In a device for reconditioning razor blades, a frame, a pair of abrading rolls relatively in spaced parallelism journaled in said frame for a limited arc of rotation in alternate directions and having portions of its peripheral surfaces exposed to opposite open sides of the frame, a blade holding support bridging said frame between the abrading rolls, rigidly supporting a double edge blade under a bowed stress, with its opposite cutting edges in bearing contact respectively against the peripheries of said rolls, the roller surfaces exposed to one open side of said frame, tractively engageable with a surface for roll rotation upon reciprocation of the frame, whereby a surface of the rolls is translated in alternate directions, each 30 respectively across a relative cutting edge of the blade to recondition the same.

2. In a device for reconditioning razor blades, a frame, a pair of abrading rolls relatively in spaced parallelism journaled in said frame for a limited arc of rotation in alternate directions and having portions of its peripheral surfaces exposed to opposite open sides of the frame, a blade holding support bridging said frame between the abrading rolls, rigidly supporting a double edge 40 blade under a bowed stress, with its opposite cutting edges in bearing contact respectively against the peripheries of said rolls, the roller surfaces exposed to one open side of said frame, tractively engageable with a surface for roll rotation upon reciprocation of the frame, for translating a surface of each roll in alternate directions, respectively across a relative cutting edge of the blade 45 to recondition the same, and means for locking the blade upon said support.

CHARLES L. WILLCOX.
